UNITED STATES PATENT OFFICE.

LUCIEN LARCHER, OF PARIS, FRANCE.

KEYLESS OR PERMUTATION LOCK.

SPECIFICATION forming part of Letters Patent No. 663,447, dated December 11, 1900.

Application filed May 29, 1899. Serial No. 718,710. (No model.)

To all whom it may concern:

Be it known that I, LUCIEN LARCHER, residing at No. 9 Rue Milton, Paris, in the Republic of France, have invented certain new and useful Improvements in Keyless or Permutation Locks; and I do hereby declare the following to be a full, clear, and exact description of the invention, such as will enable others skilled in the art to which it appertains to make and use the same.

The present invention relates to improvements in keyless or permutation locks the locking and unlocking of which are effected by the aid of a prearranged combination of a set of buttons. The cylindrical rod of each of these buttons is flattened in a different manner on two opposite sides and runs in a groove or slot of peculiar form made in the bolt of the lock, so that the said bolt cannot slide one way or the other unless the rods of the secret buttons are in a certain position brought about by their peculiar form in combination with that of the slot or groove. Upon each button-rod is fixed a toothed wheel which gears with a flexible catch, the said catch being fixed to the case of the lock. These toothed wheels can be removed without difficulty from the respective button-rod and replaced in another position, which of course at once changes the combination. The number of teeth in each wheel being fixed and one of the teeth being of a special form in order to serve as a starting-point, it thus becomes possible to open the lock without a light by successively turning the buttons tooth by tooth and counting to the number each button should represent in the combination.

I will now proceed to describe my invention in detail with the aid of the accompanying drawings, illustrating it, and in which—

Figure 1 represents a plan view of the interior of the lock with the cover-plate removed. Fig. 2 represents the outside of the lock with the cover-plate in position. Fig. 3 represents the bolt in plan detached. Fig. 4 is a plan view, detached, of a stop-piece which is placed under the bolt. Fig. 5 represents a vertical section and plan, respectively, of one of the secret-button rods. Fig. 6 is a plan view of one of the toothed wheels. Fig. 7 represents, on a larger scale, a transverse section of the lock, taken on the line *xxx*

of Fig. 1. The socket 6^a presents its narrow side and rests in the contracted part 9 of the slot in the bolt. Fig. 8 represents an elevation, partly in section, corresponding to Fig. 7, but with the socket 6^a resting in one of the enlarged parts of the slot in the bolt and turned ninety degrees, so as to present a flat side 8. Fig. 9 is a plan view, detached, of the ring or disk which bears inscriptions. Fig. 10 is a detached view of the main bolt, the sockets in the slot therein, and the yielding plate.

An ordinary lock-case 1 contains the sliding-bolt 2 and the lock-bolt 3, which latter is caused to move by turning the respective buttons 2^a and 3^a. Outside the lock the same form and appearance as those of the secret buttons 4^a, 4^b, 4^c is preferably given to these two buttons. The buttons 4^a, 4^b, and 4^c on one side of the door are each riveted on a screw, (see Figs. 7 and 8,) the length of which corresponds to the thickness of the wood. The buttons on the other side of the door form nuts and are screwed on the screws. These buttons are made fast to their spindles and provided with a bush, also fast thereon, having on their sides squares which fit into square holes 5 in the toothed wheels 5^a, 5^b, and 5^c to prevent the buttons from being spontaneously displaced and altering the combination. These toothed wheels are fitted loosely on the top part 7 of the sockets 6^a, 6^b, and 6^c, the special form of which can be seen in Fig. 5. The screw of each of these buttons passes through the hole 6 of the socket, which thus forms what I call the "flattened rod" of the combination-buttons. This socket or button rod runs through the slot or groove 9 of the bolt 3 and can turn freely in the circular enlargements 9^a therein, as shown in Fig. 7. Its round foot 10 turns freely in a corresponding hole in the outer wall of the lock-case. The part of the socket which runs along groove 9 of the bolt is flattened on the two opposite sides 8, and its form corresponds to the groove 9, so that the bolt 3 can shoot forward or backward when the three sockets 6^a, 6^b, 6^c are in the position in which the narrow parts 9 of the groove can pass on them. This is shown in Fig. 8. A movable piece 11, worked by a spring 12, is placed below the bolt 3. This part has three slots or grooves 11^a, 11^b, and

11^c and serves to fix the sockets, and consequently the combination-buttons, in the position where the bolt can run on the sockets. Rings 19, such as shown detached in Fig. 9, 5 bearing the inscription of figures or letters of the alphabet, are fixed under the buttons on the respective screws. The rings are loose on the screw and by tightening the buttons they are fixed in such a position that their 10 inscription corresponds to the secret cipher. On pivots fixed in the lock-case the catches or pawls 14 turn, each being moved by a spring, and they give with the toothing of the respective wheels 5^a, 5^b, and 5^c. The top 15 cylindrical parts of the sockets or button-rods 6^a 6^b 6^c are filed on the under face 6^e, and against this face abuts a movable plate 15, which is acted upon by a spring 16 and can slide vertically on the bolt 3, guided on 20 pivot 17. Its backward or downward path is limited by a stop-piece or stump 18 on bolt 3. This movable plate plays an important part in the invention, for it makes all the button-rods mutually dependent on each 25 other—that is to say, that on endeavoring to discover the secret combination by successively and gradually turning the buttons and at the same time trying to turn the button 3^a of the lock-bolt 3 the movable 30 plate 15 transmits the movements of each of the buttons to the others, so that it becomes impossible to determine by touch the position which each button should occupy to reveal the secret combination, which might 35 happen if this plate did not exist, for the combination-buttons not being made interdependent it is easier to feel by touch of the buttons when the bolt no longer strikes against the rod of the respective button examined.

40 The general working is as follows: The peculiar form of the tooth σ of each of the wheels 5^a 5^b 5^c makes it possible for the wheels to turn indefinitely in one direction, (left to right in Fig. 1,) whereas in the opposite direction 45 their rotary motion is stopped when the catch 14 comes behind the tooth σ . Taking the number "357" as the secret combination, one is to work as follows: After placing in position the bolt 3 the three rods or sockets 6^a, 6^b, and 50 6^c are introduced into the enlargement 9^a of the bolt, the foot of which sockets is placed in the corresponding holes on the bottom of the lock. These three rods must be turned so that their flat parts may pass into the narrow 55 parts 9 of the groove, and the bolt is pushed half-way, so that the rods are maintained in place. Then one of the toothed wheels is placed on each rod, and after adjusting the catches 14 all the wheels are to be 60 brought to the stop-tooth σ —that is to say, to stoppage of the right-to-left movement. The wheel 5^a is then to be turned three teeth, the wheel 5^b five teeth, and the wheel 5^c seven 65 teeth. The cover-plate is then placed on the case and the wheels are fixed in the given position by introduction therein of the button-screws. If the rings 19 bear the inscription of

figures, one must take care to arrange them so that the numerals "3" "5" "7" may be at the top before tightening the button-nuts 4^a, 4^b, and 4^c. To release the lock-bolt for opening, it then suffices to turn the three buttons 4^a, 4^b, and 4^c to the outside of the door, so that their rings may form at the top the number "753," whereas inside the door the number 75 of the secret combination is "357." When it is desired to unlock the lock without a light, one first brings back the three buttons to the stoppage-tooth σ and then turns them tooth by tooth, counting three teeth for the button 4^a, 80 five for button 4^b, and seven for button 4^c. It can then be seen that this combination will render even useless all inscription on the rings. Suppression of the inscriptions will, in fact, often be desirable, for they readily 85 aid discovery of the combination by inquisitive persons. The springs of catches 14 are powerful enough to enable one to turn the buttons, counting tooth by tooth. When there is any reason for preserving during a certain 90 time full movability of the bolt, one draws the plate 11 a little backward. The narrow parts of the slots or grooves 11^a 11^b 11^c then grasp the rods 6^a 6^b 6^c and prevent all turning motion of the buttons, so that the bolt 95 can shoot freely forward and backward without any involuntary or accidental disarrangement intervening to change the positions given to the buttons.

It is evident that the number of buttons 100 may vary; but from what precedes it clearly results that a lock with three buttons or even two buttons presents every guarantee of safety, the simplicity of the mechanism enabling a change to be made at any moment 105 of the combination.

By suppressing the sliding bolt 2 of the lock, which, by the way, is no feature in the present invention, the lock is transformed 110 into a safety-bolt for doors which are opened and shut from outside and inside. This safety-bolt can also be used on cupboards, bags, and other objects or articles with but small obvious adaptations if one replaces the buttons on the inner side by a simple nut. 115

I claim—

1. In a keyless or permutation lock or safety-bolt, the combination of the secret buttons with sockets flattened on two opposite sides, a slot or groove in the bolt, a movable plate abutting against the sockets, a spring always 120 pressing said plate thereby transmitting to all the buttons simultaneously the movements given to any one of them, as described and set forth.

2. In a keyless or permutation lock or safety-bolt, the combination of the secret buttons with flattened sockets preventing displacement of the sliding bolt until they are turned into a certain position corresponding to a peculiar form of slot or groove in the bolt, a bolt provided with a slot or groove, a movable spring-pressed plate, the spring, toothed wheels fitted on the flattened sockets, and 130

spring catches or pawls gearing with the toothed wheels, as described and set forth.

3. In a keyless or permutation lock or safety-bolt, the combination of the secret buttons with flattened sockets preventing displacement of the sliding bolt until their position corresponds to a peculiar form of groove or slot in the bolt, a bolt provided with the groove or slot, a movable spring-pressed plate, the

10 spring, spring catches or pawls fitted in the lock-case, toothed wheels fitted loosely on the flattened sockets, a screw passing through

the sockets and having a special square part for maintaining in position the toothed wheels, and a special stop-tooth on each of 15 the toothed wheels, as described and set forth.

In testimony that I claim the foregoing as my invention I have signed my name in presence of two subscribing witnesses.

LUCIEN LARCHER.
